UNITED STATES PATENT OFFICE.

HORACE P. FARRINGTON, OF BROOKLYN, NEW YORK.

COMBINATION-TOOL.

1,107,276.

Specification of Letters Patent. Patented Aug. 18, 1914.

Application filed March 1, 1913. Serial No. 751,606.

To all whom it may concern:

Be it known that I, HORACE P. FARRINGTON, citizen of the United States, residing at Brooklyn, in the county of Kings and State 5 of New York, have invented certain new and useful Improvements in Combination-Tools, of which the following is a specification.

This invention relates to an improved instrument suitable for use by machinists, mechanics, engineers or the like.

The primary object of the invention contemplates the provision of a compact, simple and inexpensive device which combines 15 the advantages of a square, wire gage, thread gage, bevel gage, sheet metal gage, rule, calipers and wrench.

Another object of my invention resides in the provision of a tool of the above character which is simple in construction and, 20 reliable in operation, yet fully capable of serving the purpose for which it is designed.

A further object of the invention is to provide an ordinary square, upon which the 25 several tools or instruments comprising my invention are mounted, the tools being disposed in relation to the said square, in such a novel and peculiar manner as to provide a neat, compact and useful device.

The above and additional objects are accomplished by such means as are illustrated 30 in their preferred embodiment in the accompanying drawings, described in the following specification and then more particularly 35 pointed out in the claim which is appended hereto and forms a part of this application.

In describing my invention in detail reference will be had to the accompanying 40 drawings wherein like characters denote like or corresponding parts throughout the several views, and in which:—

Figure 1 is an elevation of an instrument or device constructed in accordance with my 45 invention. Fig. 2 is a transverse sectional view taken through the stock of the tool, the blades being shown in elevation, and the plates being inclosed within the cut-out or recess provided therefor. Fig. 3 is a fragmentary view illustrating the connection between the wrench head and the square stock. Fig. 4 is an elevation of a portion of the 50 tool, showing the construction of the bevel gage, and Fig. 5 is an elevation of a modified form of wire gage.

Proceeding now to the description of the

drawings wherein is illustrated the preferred form of my invention the numeral 1 designates the stock of an ordinary try-square, to one end of which is secured in 60 the usual manner, a blade 2 provided with graduation marks 3 designating inches and the fractions thereof. An elongated aperture or opening 4 is formed within the blade for the purpose of measuring wire of various size, as one edge of the said aperture is provided with graduation marks as shown at 65 5 whereby such measurement is greatly facilitated. Pivotaly mounted within the stock 1, through the medium of a pin 6 are 70 a plurality of plates or blades 7, the edges of which are provided with screw-thread gages 8, formed within the plates 7 near the ends thereof. One edge of the plates 7 has formed therein a plurality of cut out portions 9, the same varying in size throughout the several plates employed in connection with the invention, thereby forming a wire or sheet metal gage, the purpose of which 75 is obvious. A cut out portion or recess 10 is 80 formed within the stock 1, the said plates 7 being pivoted therein and adapted to normally fold within the said recess when not in use, the pivoted end of the plates being rounded as at 11 to facilitate the opening 85 and closing of the plates as desired. When folded within the recess, the blades 7 will in no way interfere with the application of the tool for the various other purposes for which it is designed, the blades being so arranged as to permit the withdrawal of one 90 blade at a time for determining the pitch of the screw thread in question.

Upon the opposite end of the stock 1 from the blade 2, I provide a wrench head 12, the 95 same being adjustably mounted in alignment with the stock by means of a longitudinally extending exteriorly screw threaded stem 13 fitting within the said stock and extending throughout a portion of the length thereof, 100 the said head 12 being loosely mounted upon the stem 13 so as to slide independently thereof. A head 14 is formed upon one end of the said stem and is adapted to fit within a recess 15 formed within the wrench head 105 12, whereby a turning of the said head 14 will permit separation of the jaws of the wrench formed by the inner face 16 of the head and the outer end 17 of the stock. A rule 17', either formed integrally with or 110 secured to the head 12, projects from one edge thereof and is fitted within a longitudi-

- nally extending slot 18 formed within one face of the stock 1, the said rule 17' having a flange 18 formed upon each edge thereof and extending throughout its entire length, the flange fitting within the said recess 18 for retaining the rule in proper place and guiding the same during the opening and closing of the wrench head 12. The provision of the rule 17' permits use of the device as calipers for determining the diameter of pipes, rods or similar articles, the said articles fitting between the faces 16 and 17 after proper adjustment has been obtained by the manipulation of the head 12.
- 15 A bevel gage 19 having a straight edge 20 is pivotally mounted upon the stock 1, near the intersection point of the said stock and the blade 2, such pivotal mounting being created through the medium of a thumb-screw 21. By loosening the screw 21 the gage 19 may be swung so as to bring the straight edge 20 at various angles indicated as at 22 upon the stock 1. Lateral adjustment of the gage 19 is permitted by reason 25 of a slot 23 formed within the said gage.
- Referring now to the modification shown in Fig. 5 the elongated aperture 4 of the preferred form is dispensed with and the blade 30 in the modification is provided with 30 a plurality of apertures 31 varying in size as desired, each aperture designating the size of the wire or twist-drill acted upon, thereby forming an efficient twist-drill or wire gage of the above character.
- 35 It will be seen from the above, taken in connection with the accompanying drawings that the several tools or instruments comprising my invention are disposed or formed upon the try-square in a neat, compact and

highly efficient manner; and that the several 40 try-square attachments, when folded, occupy but a minimum amount of space.

It will be understood that the above description and accompanying drawings comprehend only the general and preferred embodiment of my invention and that various minor changes in the details of construction, proportion and arrangement of parts may be made within the scope of the appended claim and without sacrificing any of the advantages of my invention.

Having thus fully described my invention, what I claim as new and desire to secure by Letters Patent, is:—

A tool including a body portion having a 55 longitudinal groove formed in one face thereof, a rule strip fitting said groove, said strip being adjustable longitudinally relatively to the said body, a head portion integral with the said strip, the latter serving 60 as a means preventing movement of the head laterally independently of the body, an exteriorly threaded shank operating within a threaded bore therefor extending longitudinally of the body and in parallel spaced relation to said groove, said shank extending through an opening therefor within the said head, and a knob formed upon the shank, said knob operating within a recess of the 65 head to adjust the head and rule relatively 70 to the body, as and for the purpose set forth.

In testimony whereof I affix my signature in presence of two witnesses.

HORACE P. FARRINGTON.
